9008574 8/1990 WIPO ..... **441/64***Primary Examiner*—Kay H. Chin[57] **CLAIM**The ornamental design for a open instep swim fin, as
shown and described.**DESCRIPTION**FIG. 1 is a perspective view of my open instep swim fin;
FIG. 2 is a top view thereof;
FIG. 3 is a front view thereof;
FIG. 4 is a right side elevational view thereof;
FIG. 5 is a bottom view thereof;

FIG. 6 is a rear view thereof;
FIG. 7 is a left side elevational view thereof;
FIG. 8 is a perspective view of a second embodiment of
the open instep swim fin;
FIG. 9 is a top view of the FIG. 8 embodiment;
FIG. 10 is a rear view of the FIG. 8 embodiment;
FIG. 11 is a right side elevational view of the FIG. 8
embodiment with a left side elevational view being
substantially a mirror image thereof;
FIG. 12 is a rear view of the FIG. 8 embodiment;
FIG. 13 is a bottom view of the FIG. 8 embodiment;
FIG. 14 is a perspective view of a third embodiment of
the open instep swim fin;
FIG. 15 is a top view of the FIG. 14 embodiment;
FIG. 16 is a front view of the FIG. 14 embodiment;
FIG. 17 is a right side elevational view of the FIG. 14
embodiment with the left side elevational view being
substantially a mirror image thereof;
FIG. 18 is a rear view of the FIG. 14 embodiment;
FIG. 19 is a bottom view of the FIG. 14 embodiment;
FIG. 20 is a perspective view of a fourth embodiment of
the open instep swim fin;
FIG. 21 is a top view of the embodiment shown in FIG.
20;
FIG. 22 is a front view of the embodiment shown in
FIG. 20;
FIG. 23 is a right side elevational view of the FIG. 20
embodiment with the left side elevational view being
substantially a mirror image thereof;
FIG. 24 is a bottom view of the FIG. 20 embodiment;
and,
FIG. 25 is a rear view of the FIG. 20 embodiment.

FIG. 4.

FIG. 5.

FIG. 6.

FIG. 7.

FIG. 8.

FIG. 10.

FIG. 11.

FIG. 9.

FIG. 13.
